FIG. 1 is a front elevational view of a combined safety equipment container and closure therefor showing my new design;

FIG. 2 is an elevational view looking from the left of FIG. 1;

FIG. 3 is an elevational view looking from the right of FIG. 1;

FIG. 4 is a top plan view with the closure removed;

FIG. 5 is a front elevational view with the closure removed;

FIG. 6 is an elevational view partly in section looking from the left of FIG. 5;

FIG. 7 is a view similar to FIG. 5 but showing a modified form of my new design; and

FIG. 8 is an elevational view looking from the left of FIG. 7.

The rear view of the container, in both forms shown in the drawings, is unornamented and concave, as shown.

I claim:

The ornamental design for a combined safety equipment container and closure therefor, as shown and described.
